CLAIM

The ornamental design for a liquid dispenser, as shown and described.

DESCRIPTION

FIG. 1 is a front perspective view of liquid dispenser, showing my new design;

FIG. 2 is a side elevation, the opposite side being a mirror image of the figure shown;

FIG. 3 is a top plan view thereof;

FIG. 4 is a bottom plan view thereof;

FIG. 5 is a front elevation;

FIG. 6 is a rear elevation; and

FIG. 7 is a side elevation of an alternate embodiment thereof, the only difference being in the relatively shorter length of the wand portion.

FIG. 5.

FIG. 6.

FIG. 2.

FIG. 3.

FIG. 4.

FIG. 7.

FIG. 6

FIG. 5
